UNITED STATES PATENT OFFICE.

ELISHA BARTON CUTTEN, OF MINNEAPOLIS, MINNESOTA.

ELECTROLYTIC CELL.

1,397,799.

Specification of Letters Patent.

Patented Nov. 22, 1921.

Application filed June 25, 1920. Serial No. 391,614.

To all whom it may concern:

Be it known that I, ELISHA B. CUTTEN, a citizen of the United States, and a resident of Minneapolis, county of Hennepin, State 5 of Minnesota, have invented certain new and useful Improvements in Electrolytic Cells; and I do hereby declare the following to be a full, clear, and exact description of the invention, such as will enable others skilled 10 in the art to which it appertains to make and use the same.

The invention relates to an electrolytic cell more particularly adapted to the decomposition of a sodium chlorid solution, 15 with the formation of chlorin and hydrogen which are taken off in gaseous form and the formation of sodium hydrate or caustic soda. The invention has for its object to provide a simple and efficient form of apparatus in 20 which the internal resistance of the cell will be maintained at a low minimum, the collection of deposits of impurities tending to impair the action of the device will be obviated and the several products resulting from the 25 electrolytic action—to-wit, chlorin gas, hydrogen gas, and a strong solution of caustic soda—may be severally recovered and may be drawn from the apparatus in a comparatively pure condition.

30 The apparatus is illustrated in the accompanying drawings, in which:—

Figure 1 is a sectional elevation of one of the cells;

Fig. 2 is an enlarged sectional elevation 35 of the support and connecting means for the anode;

Fig. 3 is an enlarged fragmentary sectional elevation of the casing and the foraminated lining therefor.

40 Referring to the drawings 1 indicates a tank or vessel preferably made of iron and constituting the cathode member of the cell, said tank being provided with a conical bottom 2, which projects inwardly of the tank 45 and serves as the primary support for the anode. The interior of the tank is provided with a liner 3, which is formed as a cylinder of sheet iron, having an imperforate upper section provided with a marginal flange 50 which is connected to the upper rim of the tank by a hermetic seal, formed preferably by welding the flange of the liner to the rim of the tank thereby forming an annular

chamber between the tank walls and the imperforate section of the liner. The major 55 portion of the liner is perforated by means of a multiplicity of V-shaped openings formed by punching out generally triangular tongue members 4 which are bent outwardly in the punching operation and engage in the inner 60 surface of the wall of the tank 1. The said liner 3 extends to near the bottom of the tank and provides an annular chamber or channel about the inner walls of the tank from the top to the bottom thereof to facilitate 65 the movement of the heavier products of the electrolytic action toward the bottom of the tank and a concurrent movement of certain of the lighter products and wash water toward the top of the tank, as will be 70 more fully explained hereinafter.

Also secured to the upper rim of the tank, and connected thereto by a fluid-tight joint, as by electric welding, is an annular partition plate 5 having a horizontal flange 6 75 which may overlie the flange connecting the liner 3 with the rim of the tank. Said partition plate is preferably formed by sheet iron or other appropriate material coated with a chemical resisting medium such as japan, 80 varnish, enamel, or the like so that the partition will not be attacked by the electrolyte or any of the products evolved therefrom. The partition 5 is of sufficient length, so that its lower edge is well submerged in the electrolyte and forms an annular chamber to receive 85 the gas freed at the cathode, said gas being prevented from escaping from the chamber by the liquid seal formed by the immersion of the lower end of the partition 5 90 in the electrolyte. A discharge pipe 17, provided with a suitable valve, communicates with the annular chamber aforesaid and affords means for drawing off the gas which accumulates in the chamber. To facilitate 95 the discharge of the gas, the pipe 17 is preferably connected with a pump or other exhaust apparatus which will induce a steady flow of the gas from the chamber.

Mounted on top of the tank is a spider-like ring 11 which serves to support a generally bell-shaped dome or receiver 8, made of glass, stone-ware or other suitable material, which is not affected by the electrolyte or the reaction products. Said receiver extends 105 well within the outer tank 1 and is

provided near its middle with an annular flange 9 which rests upon a suitable ring 10 of packing interposed between the receiver and the spider ring 11, so that the receiver 5 is supported firmly but yieldingly within the tank. The upper end of the receiver is provided with a supply nozzle or inlet 12 for the solid chemicals employed in the cell, which is surrounded by an up-standing 10 flange 13, said inlet being closed by a cap member 14 made of similar material to that of the receiver and sealed within the annular chamber formed by the neck of the inlet 12 and flange 13 by means of a suitable plastic material such as paraffin or the like, indicated at 15. A discharge pipe 16 is connected with the upper end of receiver 12 and is also connected with an exhaust pump or other suitable means for withdrawing the 15 gases which collect in the receiver 12.

Mounted on the upper flat surface of the concave bottom 2 of the tank is a deflector and supporting member 20, made of stoneware, glass or the like, provided with an 25 annular flange 21 on its top, which is adapted to receive the base of a generally cylindrical anode 31, which latter is preferably made of graphitic carbon provided with longitudinal flutes on its side and terminating 30 in a conical upper end. The lower end of the anode is fixed in the support 20 by means of a suitable cement 32.

Secured to the under face of the tank bottom 2 is a stuffing box comprising an 35 upper flanged section 22 bolted to the tank bottom, a lower telescoping flange section 25 which is adjustably secured to the upper flange 22 by means of bolts 27, said flanges inclosing two insulating ring members 23 40 and 24 between which a suitable insulating fibrous packing 26 is disposed as more particularly illustrated in Fig. 2. Fitted within the insulating packing rings 23 and 24 is a cylindrical connector member 30, preferably made of the same type of carbon as the anode 31, the upper end of which connector is tapered to fit a correspondingly tapered recess in the base of the anode 31. Suitable current leads 35 and 36 are connected to terminal 30 and the outside wall 50 of the tank respectively.

Disposed about the conical base of the tank, below the deflector plate 20, is an annular manifold or supply header 42 provided with a series of discharge openings on its outer face, said manifold being connected to a supply pipe 40 which latter is controlled by a suitable valve 41, so that when water or other washing medium is supplied 55 to the header it will be delivered in the form of a series of fine jets or streams directed toward the inner wall of the tank 1 and thence upwardly between the tank wall and the liner 3. Near the upper rim of the tank 60 1, and opposite the outlet pipe 17, there is

provided a discharge pipe 45 fitted with a suitable control valve 44. Near the bottom of the tank 1 a suitable discharge faucet 50 is provided from which the reaction products collected in the bottom of the tank are discharged.

It is to be understood, that instead of forming the anode 31 and connector member 30 as separate elements they may be constructed of a single piece of carbon, but in 75 either event it is desirable that the portion of the anode which passes through the stuffing box be treated with paraffin or similar material which would prevent the carbon from absorbing the liquid in the tank and 80 permitting the absorbed liquid to seep out by reason of the porosity of carbon.

The operation of the apparatus in electrolyzing a solution of sodium chlorid or brine, for example, is as follows. A relatively strong solution of brine is supplied to the tank and then a quantity of salt crystals is added through the inlet 12 until the level of the liquid in the tank rises above the lower end of the partition 5. This will also 90 produce a submersion of the lower end of receiver 8 in the liquid and salt crystals. Current is then applied, entering by way of the conductor 35 and passing through the anode 31 and the salt solution, thence to the 95 liner 3 and the iron tank 1 and the conductor 36 back to the source. The effect of the current passing from the surface of the anode 31 through the liquid breaks up the sodium chlorid solution, liberating the chlorin 100 which passes directly upward from the anode surface and collects in the receiver 8. The liberated sodium which tends to pass to the cathode, represented by the wall of the tank 1, combines with the elements of the 105 water present to form sodium hydrate or caustic soda, thereby liberating part of the hydrogen of the water at or adjacent to the cathode surface formed by the tank wall and the liner 3, which latter also forms a 110 component part of the cathode. The perforations in the liner are effective in diverting the heavier caustic soda solution downward through the space between the liner and the tank wall, so the solution settles quietly and 115 collects at the bottom of the tank without any material tendency to diffuse throughout the lighter brine solution. Furthermore, the tongues 4 on the liner, being in electrical contact with the cathode wall 1, are effective in preventing any material diminution 120 of the current which would normally be produced by the resistance of the heavier caustic soda solution adjacent to the cathode surface. The liberated hydrogen rises freely 125 through the liquid adjacent to the liner, any portion of the gas formed between the liner and the tank wall 1 pass through the perforations in the liner, and the total volume of liberated hydrogen collecting in the annular 130

space between the partition plate 5 and the imperforate upper section of liner 3. The operation of the pumps or other evacuating devices connected with the chlorin outlet 16 and the hydrogen outlet 17 is so regulated that the degree of vacuum produced in the hydrogen space is never in excess of that produced in the top of receiver 8, so that the two gases are maintained effectively separated throughout the operation of the cell and are delivered therefrom in substantially pure condition. The relatively strong solution of caustic soda which collects at the bottom of the tank remains quiescent there in with little or no tendency to diffuse throughout the supernatant lighter salt solution, and is drawn off at the tap 50 as occasion may require.

It frequently occurs when more or less impure salt or brine solutions or salt crystals are employed that the impurities, which are usually present in the form of other compounds or solutions, will decompose at the surface of the anode, with the formation 25 of other compounds, usually in the form of hydrates, which tend to collect at the surface of the cathode and thereby materially increase the internal resistance of the cell and commensurately diminish the efficiency 30 of the latter. This is particularly true of the brine solutions and salt crystals which have been contaminated with magnesium chlorid, or bittern, which decomposes at the anode surface, with the result that the free 35 magnesium combines with the water of the solution and forms magnesium hydrate, which collects on the inner wall of the tank 1 and very materially increases the resistance to the passage of the electrical current. 40 In order to overcome this difficulty the header pipe 42 is provided, so that when the valve 41 in the water supply pipe 40 is opened a series of fine jets or streams of water is delivered radially against the tank 45 walls and as the water is much lighter than the brine solution it rises in a rapid current between the tank wall 1 and the liner 3 and washes the surfaces free of the accumulated bittern or hydrate of magnesium, which is 50 discharged through the outlet pipe 43.

The operation of the cell as indicated is continuous and requires only the addition of salt crystals and water from time to time to maintain the brine solution at a point of 55 substantial saturation, the crystals being added through the supply opening 12 at the top of receiver 8 and the water being supplied through the pipe 40 and header 42. It will be understood, of course, during the 60 normal operation of the apparatus, the valves 41 and 44 are closed and the chlorin and hydrogen pipes 16 and 17 are opened and subject to the action of the pumps or other ejector apparatus to induce a negative 65 pressure in the chlorin and hydrogen re-

ceiving spaces, to withdraw these gases as rapidly as they are formed, said pipes delivering the gases to appropriate receptacles.

What I claim is:—

1. An electrolytic cell comprising a tank 70 constituting a cathode, an anode therein, a receiver supported from the top of the tank and immersed in the electrolyte surrounding the anode, and a perforated liner spaced from the inner wall of the tank. 75

2. An electrolytic cell comprising a tank constituting a cathode, an anode therein, a receiver supported from the top of the tank and immersed in the electrolyte surrounding the anode, and a perforated liner 80 of similar material to the tank spaced from the inner wall of the latter and having multiple points of contact therewith.

3. An electrolytic cell comprising a tank constituting a cathode, an anode therein, a 85 receiver supported from the top of the tank and immersed in the electrolyte surrounding the anode, a perforated liner spaced from the inner wall of the tank having an imperforate upper section sealed to the tank 90 wall to provide an annular chamber, a valved outlet from said chamber, and a supply header located adjacent to the bottom of the tank wall to direct washing water between the wall and the liner. 95

4. An electrolytic cell comprising a tank constituting a cathode, an anode therein, a receiver supported from the top of the tank and immersed in the electrolyte surrounding the anode, a perforated liner 100 spaced from the inner wall of the tank having an imperforate upper section sealed to the tank wall to provide an annular chamber, a valved outlet from said chamber, and an annular supply header located adjacent 105 to the bottom of the tank wall to direct washing water between the wall and the liner.

5. An electrolytic cell comprising a tank constituting a cathode, an anode therein, 110 a receiver supported from the top of the tank and immersed in the electrolyte surrounding the anode, an annular partition spaced from the tank wall and hermetically sealed to the top thereof and surrounding 115 the receiver, and gas outlets connected with the receiver and the space between the tank wall and the annular partition.

6. An electrolytic cell comprising a tank constituting a cathode, an anode therein, 120 a receiver supported from the top of the tank and immersed in the electrolyte surrounding the anode, an annular partition spaced from the tank wall and hermetically sealed to the top thereof and surrounding 125 the receiver, gas outlets connected with the receiver and the space between the tank wall and the annular partition, and means for withdrawing the gases from the receiver and annular space aforesaid. 130

7. An electrolytic cell comprising a tank constituting a cathode, a receiver mounted on the top of the tank and immersed in the electrolyte, and an anode mounted in the bottom of the tank and projecting upwardly toward the receiver; the mounting for said anode comprising a flanged deflector plate in which the anode is seated, and an insulating stuffing box secured to the

bottom of the tank through which an ex- 10 tension of the anode projects.

In testimony whereof I affix my signature, in presence of two witnesses.

ELISHA BARTON CUTTEN.
